UNITED STATES PATENT OFFICE.

JOSEPH P. MAXFIELD, OF MAPLEWOOD, NEW JERSEY, ASSIGNOR TO WESTERN ELECTRIC COMPANY, INCORPORATED, OF NEW YORK, N. Y., A CORPORATION OF NEW YORK.

ACOUSTICAL AID FOR DEAF PERSONS.

1,422,877.

Specification of Letters Patent. Patented July 18, 1922.

Application filed January 2, 1920. Serial No. 348,868.

To all whom it may concern:

Be it known that I, JOSEPH P. MAXFIELD, a citizen of the United States, residing at Maplewood, in the county of Essex and State 5 of New Jersey, have invented new and useful Improvements in Acoustical Aids for Deaf Persons, of which the following is a full, clear, concise, and exact description.

This invention relates to devices for improving the hearing of deaf or partially 10 deaf persons and its object is to bring such a person into natural acoustical relation to his environment.

Among the many devices which have been 15 developed as an aid to deaf persons the most successful has undoubtedly been the type which which makes use of a small microphonic telephone transmitter in combination with a head telephone receiver and a small 20 dry battery. Such devices have however some serious defects, one of the most objectionable being that extraneous room noises and street noises are so blended in with the spoken sounds that it is extremely difficult for 25 the listener to focus his attention on the speech and to separate it mentally from the extraneous disturbances. Another objection is that in order that these devices may produce a sufficient volume of sound to give effective aid in hearing recourse has been had 30 to extremely sensitive microphones, which "break" badly when suddenly jarred or when they are subjected to unusually loud sounds and thus produce disagreeable and 35 often painfully loud shocks to the ear. These microphones are furthermore inherently liable to produce sizzling and frying noises which add still further to the difficulty of focusing the attention on the sound 40 which it is desired to hear.

The present invention aims primarily at the elimination of the above noted defects. It makes use of a form of microphone which, while fairly sensitive to small sounds, is not 45 proportionately more sensitive to sounds of greater magnitude so that sudden shocks and jars do not produce excessively loud sounds in the telephone receiver. This microphone is used in combination with a distortionless 50 amplifier, preferably of the audion type, whose output is made adjustable to give any desired volume of sound depending on the sensitiveness of the ear, the intensity of the sound and the prevalence of disturbing 55 noises. Preferably two of these microphone-

amplifier systems are employed, each leading to a separate telephone receiver. The microphones are located from ten to fourteen inches apart with their diaphragms in approximately the same plane. One receiver 60 is worn on each ear, the right-hand receiver being connected to the right-hand microphone-amplifier and the left-hand receiver being connected to the left-hand microphone-amplifier. The use of a binaural system of 65 this sort has been found to be remarkably efficient in enabling the user to focus his attention on the particular sound which he desires to hear, for by orienting the dual microphone set so that the microphones lie 70 in a plane at right angles to the source of sound the same ability to concentrate is noticed as when a person of normal hearing turns to face the speaker.

The binaural system has the further advantage of enabling the user to determine the direction from which a sound is coming, to distinguish for example, which one of a number of persons is speaking. This effect is due not to a difference in the intensity of 75 the sound reaching the two ears but to the difference in phase of the sounds at the two ears, so that the advantages above noted are available to those who have more difficulty in hearing with one ear than with the other. 80 Such differences in the sensitiveness of the two ears can, in the present invention, be compensated for by adjusting the degree of amplification in the two amplifying circuits so that they will deliver a greater volume 85 of sound to the less sensitive ear.

The invention will be more clearly understood by referring to the accompanying drawing in which Fig. 1 gives a diagrammatic representation of the system of this 95 invention; Fig. 2 shows in detail the construction of one of the microphone elements, and Fig. 3 shows an arrangement for mounting the microphones so that they may be oriented easily.

Referring to Fig. 1, two microphones 4 and 5 are connected in series with batteries 6 and 7 and the primary windings of induction coils 8 and 9 respectively. The secondary windings of the induction coils 8 and 100 9 are connected to the terminals of the resistances 10 and 11 which in turn are bridged across the input circuits of two vacuum tube amplifiers 12 and 13, having the usual heated cathodes 14, 15, control electrodes 16, 17, 110

and anodes 18, 19. The temperature of the filaments and consequently the output of the amplifiers can be readily adjusted by means of the rheostats 20, 21, located in the filament circuits. The output circuits of the amplifiers 12 and 13 are connected respectively to the primary windings of the transformers 22 and 23 while the secondary windings of these transformers are connected to 10 the two telephone receivers 24 and 25.

The microphones 4 and 5 are preferably of the air-damped type shown in Fig. 2 having a vibratory diaphragm 26 securely clamped between a perforated front plate 27 15 and a back plate 28. The spaces 29 and 30 between the diaphragm and the front and back plates respectively are made extremely small, of the order of .005 inch or less so that there is a thin layer of air on either side of 20 the diaphragm which effectively limits the amplitude of its vibration. The back plate 28 is provided with an annular groove 31 which communicates with the space 30 and acts as an air reservoir. This air reservoir 25 also connects with the outside air through a series of small openings 32 located at intervals along its length.

The back plate 28 is furthermore provided with a central cavity 33 to accommodate 30 the microphone button 34 which is adjustably mounted on the back plate 28 and insulated therefrom by the insulating washers 35 and 36. The microphone button 34 carries a fixed electrode 37 and a mass of 35 granular carbon 38. The movable electrode 39 is attached to the diaphragm 26 or may be a gold plated surface thereon. Between the edge of the button cup and the front electrode 39 is a resilient washer 40 preferably 40 of felt.

The two microphones 4 and 5 are preferably mounted on a stand such as that shown in Fig. 3 comprising a base portion 41 and an upright standard 42 on which is mounted 45 a rotatable collar 43 carrying laterally extending arms 44 to the ends of which the microphones 4 and 5 are attached. This arrangement is primarily adapted to use on a table or desk and enables the user to orient 50 the plane of the microphones so that it will lie at right angles to the direction from which the sound, which it is desired to hear, is coming.

What is claimed is:

55 1. A system for enabling a deaf person

to place himself in natural acoustical relation to his environment comprising a pair of microphones mounted with their diaphragms in the same plane, means for changing the angular position of said plane with reference to a sound source, a pair of telephone receivers, one for each ear of said deaf person, and a separate circuit connecting each of said receivers with a corresponding one of said microphones. 60

2. A system for enabling a deaf person to place himself in natural acoustical relation to his environment comprising a pair of microphones mounted with their diaphragms in the same plane, means for changing the angular position of said plane with reference to a sound source, a pair of telephone receivers, one for each ear of said deaf person, a separate circuit connecting each of said receivers with a corresponding one of 70 said microphones, and a current amplifier in each of said circuits. 75

3. A binaural system for deaf persons comprising a pair of microphones having highly damped vibrating systems, a corresponding pair of telephone receivers, a separate amplifying circuit connecting each of said microphones with the corresponding receiver, and means for adjusting the degree of amplification in said circuits. 80

4. A binaural system for deaf persons comprising a pair of microphones having air-damped vibrating systems, a corresponding pair of telephone receivers, a separate amplifying circuit connecting each of said 90 microphones with the corresponding receiver, and means for adjusting the degree of amplification in said circuits. 95

5. A system for enabling a deaf person to place himself in natural acoustical relation to his environment comprising a pair of microphones mounted with their diaphragms in the same plane, means for changing the angular position of said plane with reference to a sound source, a pair of telephone receivers, one for each ear of said deaf person, a separate circuit connecting each of said receivers with a corresponding one of said microphones, a current amplifier in each of said circuits, and means for adjusting the output of each of said amplifiers separately. 100

In witness whereof, I hereunto subscribe my name this 30th day of December A. D. 1919.

JOSEPH P. MAXFIELD.
